UNITED STATES PATENT OFFICE.

JAMES H. RAND, OF NORTH TONAWANDA, NEW YORK.

SHEATH FOR INDEX CARDS.

Application filed May 4, 1921. Serial No. 466,728.

To all whom it may concern:

Be it known that I, JAMES H. RAND, a citizen of the United States of America, and resident of North Tonawanda, in the county 5 of Niagara and State of New York, have invented new and useful Improvements in Sheaths for Index Cards, of which the following is a specification.

This invention relates to sheaths for attachment to index cards. In card indexes of various kinds it is common to provide cards which are used as supports or carriers for insert sheets or slips, guide cards, and guide tabs, with celluloid pockets, marginal 10 bindings and reinforcements which are attached as component parts of the card structures at the time of their manufacture. The principal object of the present invention is to provide separately made sheaths which 15 can be supplied to the owners or users of plain cards, and can be by them easily and quickly attached to the cards to equip them with pockets for insert or index sheets or slips, marginal bindings or reinforcements. 20 The means by which such sheaths are attached to cards in factory production are not practicable for users of indexes, and if a user who has a card system installed desires the advantages of such sheaths, he must purchase an entire new equipment and then 25 transfer the entries. The labor and expense of so doing will be apparent especially when the system contains thousands of cards as is frequently the case. With the present invention he can quickly, easily, and cheaply equip his existing system or other plain cards with the desired sheaths, without duplicating the equipment or laboriously transferring the entries. 30

In the accompanying drawings which illustrate certain embodiments of the invention—

Fig. 1 is a front view, partly broken away, of an index card with the sheath attached thereto;

Fig. 2 is an enlarged section on line 2—2 of Fig. 1;

Fig. 3 is a fragmentary perspective view of the sheath, unattached;

Fig. 4 illustrates another use of the sheath; and Fig. 5 is a sectional view showing a modification.

Referring first to Figs. 1, 2 and 3; 6 represents a card such as is used in a so-called 55 visible index having a series of overlapping cards mounted in a frame with their free

edges projecting one beyond another to expose index characters. The supporting and spacing member, which may be of any desired form, is indicated at 7.

The sheath, shown in Fig. 1 as attached to the lower or free margin of the card 6, consists of a piece of sheet material, preferably sheet celluloid which is both transparent and resilient, folded to form a trough having a front wall 8 and a rear wall 9. The trough 60 may be formed in any convenient length and cut off by the user to a length appropriate to the desired use. One of the walls, as the rear wall 9, is preferably made wider than 65 the other wall so as to project somewhat beyond it at its free edge.

Permanently secured to the inner surface of the wider wall 9 is a strip of textile fabric 10 or other suitable sheet material, the exposed surface of which, that is the surface not attached to the wall 9, is coated with a gum or any suitable adhesive material adapted, when moistened, to stick to the surface to which it is applied. The strip 10 70 preferably extends substantially to the bottom of the trough.

The sheath is so formed that the front and rear walls are yieldingly pressed toward each other by the resiliency of the sheet celluloid of which the device is made, and tend 75 to pinch a card inserted therebetween.

To attach the sheath to the card, a wet cloth, or sponge, or the like, is drawn along the edge of the gummed fabric on the projecting part of the wider wall 9, thereby applying moisture to the gummed fabric, preferably in sufficient quantity so that the moisture will be carried into the trough 80 clear to the bottom when the card is inserted. The margin of the card is then pushed edgewise into the trough to the position shown in Figs. 1 and 2. The pinch 85 between the front and rear walls of the sheath will exert sufficient pressure to insure a firm union between the wall 9 and the card 6 without requiring the parts to be otherwise held under pressure until dry. Thus the sheath may be very easily and 90 quickly applied as it requires merely to be moistened and slipped onto the edge of the card.

While it is preferred to make the wall 9, which has the adhesive coated strip, wider than the other wall, the device would operate, though perhaps less efficiently, if the wall 9 carrying the adhesive strip were no 110

wider than the other. In this case the moisture would be applied along the crack at the entrance or top of the trough, and the moisture would tend to run into the trough on to the surface of the adhesive strip, aided by the edge of the card when the latter is inserted.

The front wall 8 preferably terminates at its free edge in an inwardly folded lip 11, which makes a smooth rounded entrance for the edge of card 6, and for an insert card or sheet 12 (Fig. 1) when the latter is inserted in the pocket formed by the sheath; but the lip 11 may be omitted if preferred.

In Fig. 4 the sheath is shown as a binding and reinforcement for the edge of a tab 6^b of a card 6^a adapted for a guide card or index element of the kind commonly used in trays or drawers. Excepting that the sheath is shorter, its construction and mode of application are the same as already described. In this instance the front wall 8 forms with the face of the tab 6^b a pocket or slideway into which an index strip bearing the desired inscription may be inserted.

In the modification shown in Fig. 5 the sheath itself constitutes the tab and is applied to a straight edge card 6^c having no tab formed thereon. The rear wall 9^a is made of sufficient width to insure a firm and stiff attachment to the margin of the card, which does not extend into the trough. The front wall 8^a terminates at about the edge of the card and is finished with an inturned lip 11^a. Thus a projecting tab structure is

formed having a hollow or tubular pocket open at its ends, into which an index slip 13 may be inserted. In this form only the gummed fabric 10 on the projecting part of the rear wall 9^a need be moistened. And as 40 only that part of the gummed fabric which is on the projecting part of the wall 9^a is used for attachment to the card body, the part of the gummed fabric which extends underneath the front wall 8^a may, if desired, 45 be omitted.

I claim:

1. A sheath for index cards comprising a piece of sheet material folded to form a trough, having one wall wider than the other, and a strip of sheet material permanently secured to the inner surface of the wider wall only of the trough, the exposed surface of the strip being provided with an adhesive adapted, when moistened, to secure 55 the sheath to the margin of an index card.

2. A sheath for index cards comprising a piece of sheet celluloid folded to form a trough having front and rear walls, the rear wall being wider than the front wall, and 60 a strip of textile fabric permanently secured to the inner surface of the rear wall only, the exposed surface of the strip being coated with an adhesive adapted, when moistened, to secure the sheath to the margin of an index card. 65

Signed by me at Boston, Massachusetts, this twenty-ninth day of April, 1921.

JAMES H. RAND.
